UNITED STATES PATENT OFFICE.

RALPH W. MORRISON, OF OMAHA, NEBRASKA.

DESIGN FOR A CABINET FOR PHONOGRAHPS.

58,614.

Specification for Design.

Patented Aug. 2, 1921.

Application filed December 26, 1919. Serial No. 347,615. Term of patent 3½ years.

To all whom it may concern:

Be it known that I, RALPH W. MORRISON, a citizen of the United States, residing at Omaha, in the county of Douglas and State of Nebraska, have invented a new, original, and ornamental Design for Cabinets for Phonographs, of which the following is a specification, reference being had to the accompanying drawing, forming a part thereof.

The figure is a perspective view of a cabi-

net for a phonograph or like machine, showing my new design.

I claim:

The ornamental design for cabinet for phonographs as shown.

In testimony whereof, I have affixed my signature in presence of two witnesses.

RALPH W. MORRISON.
